CLAIM

The ornamental design for an exercise cycle console, as shown and described.

DESCRIPTION

FIG. 1 is a perspective view of an exercise cycle console showing my design thereof;

FIG. 2 is a front elevational view thereof;

FIG. 3 is a top plan view thereof;

FIG. 4 is a side elevational view thereof; and

FIG. 5 is a bottom plan view thereof.

The broken line showing of an exercise cycle in FIGS. 1, 3 and 4 is for illustrative purposes only and forms no part of the claimed design.
